Attorney.

UNITED STATES PATENT OFFICE.

TAKAZO OSAKI, OF ITACHIBORI, OSAKA, JAPAN.

DRIVING-BELT.

1,249,661.

Specification of Letters Patent. Patented Dec. 11, 1917.

Application filed December 11, 1915. Serial No. 66,368.

To all whom it may concern:

Be it known that I, TAKAZO OSAKI, a subject of the Empire of Japan, residing at 9, Minami-dori 6-chome, Itachibori, Nishi-Ku, 5 Osaka, Japan, have invented a certain new and useful Invention Entitled Driving-Belt, of which the following is a specification.

My invention relates to a driving belt, in production whereof a number of strands, 10 each consisting of yarns from such fibrous material as cotton or hemp, closely put together, are placed in a row, and these are entwisted with one another in a manner as specified below.

15 The object of the invention is to produce a belt made of fibers, which is strong, pliable and durable, at a cheap cost, and to provide it for the transmission of power.

20 The accompanying drawing is a plan of the belt made of sixteen strands as example, and shows how these strands are entwisted to produce it according to my invention.

In the drawing, 1 to 16 show a number of strands, and 1 makes a pair with 2, 3 with 25 4, 5 with 6, 7 with 8, 9 with 10, 11 with 12, 13 with 14, 15 with 16.

The strands of each pair mentioned above are entwisted several times, to the line A—A, where the strands 1, 3, 5, 7, 9, 11, 13 are respectively entwisted with the adjoining strands only one time, *i. e.*, 1 with 4, 3 with 6, 5 with 8, 7 with 10, 9 with 12, 11 with 14, 13 with 16, and then reverting to the original state, each original pair of strands 35 is entwisted with itself several times, and at the line of B—B, the strand 2 is entwisted with 3, 4 with 5, 6 with 7, 8 with 9, 10 with 11, 12 with 13, 14 with 15 only one time, and then each original pair is again ent- 40 twisted with itself as many times as in interval between the line A—A and B—B, and at the line C—C a strand of each pair is entwisted with one of the adjoining pair in the same manner as in the line A—A, and 45 thus repeating the intertwisting of all these strands as specified from the line A—A to C—C, finally producing a flat band just like a network. This constitutes a belt of my invention.

50 The belt is to be made endless when the extremities of each strand are tied together, so that the one end of the belt closely meets the other.

The special use of the belt lies in the fact 55 that the tension each strand receives, when power is transmitted, is uniform, and also

that yarns, which constitute each strand, being equal in the stress, bear each the same load. Now, in comparison of my belt with that hitherto in use, which consists of a 60 thick fabric, or of several plies of fabric cemented together by such material as gutta percha, it is firstly found that in such a belt made of either a thick fabric or cemented fabrics, the warps only sustain the ten- 65 sion, while the wefts being in right angle thereto have no tension to bear. But in my belt, as all the yarns are arranged in the same direction, and also are entwisted in the same manner, each bears the tension evenly, 70 and accordingly the efficiency of the belt for the transmission of power is considerably great. And secondly, in a belt consisting of several plies of fabric cemented together, its inner surface in contact with the pulley 75 is less strained than its outer surface. But in my belt, as one strand reciprocally comes under the other by twisting, there happens in this case no distinction of "in" and "out", and accordingly the belt does not bring 80 upon itself any unequal strain; on this account it is strong and durable. Thirdly, as my belt requires no insertion of the weft and cementing material, its weight is consider- 85 ably reduced, and accordingly its cost mini- 90 mized, moreover a loss of energy due to the motion of the belt itself or of energy owing to the centrifugal force shall be greatly reduced. Fourthly, as my belt is pliable, it fits the pulley closely. Fifthly, in my belt, 95 the pores left between each pair of the strands act as the escape of the air film whirled into between the pulley and the belt when the motion is at highest speed, and secure close touch of the belt to the pulley. Sixthly, the strength of ordinary belt at its 100 joint even in its best state is not more than 80% of the strength inherent to the belt. But in my belt, as each strand is tied together on its extremities, the strength of its joint is never reduced at all.

I claim—

1. A driving belt comprising a plurality of pairs of longitudinally extending strands having one strand of each pair entwined 105 about one strand of the next adjacent pair at a plurality of longitudinally spaced points, and having the other strand of each pair entwined about the other strand of the next adjacent pair at a plurality of longi- 110 tudinally spaced points alternating with the first mentioned points, the strands of each

pair being entwined about each other a plurality of times between said longitudinally spaced points.

2. A driving belt as claimed in claim 1,
5 wherein the strands of the adjacent pairs at said longitudinally spaced points are entwined about each other an odd number of times and the strands of each pair are en-

twined about each other between said points an even number of times.

In testimony whereof I have affixed my signature in presence of two witnesses.

TAKAZO OSAKI.
